Attorney

UNITED STATES PATENT OFFICE.

JAMES RINARD, OF MARIETTA, OHIO.

PUMPING APPARATUS.

Application filed March 7, 1925. Serial No. 13,754.

To all whom it may concern:

Be it known that I, JAMES RINARD, a citizen of the United States, residing at Marietta, in the county of Washington and State of Ohio, have invented certain new and useful Improvements in Pumping Apparatus, of which the following is a specification.

My invention relates to pumps, such as oil or water pumps, and has particular reference to means for releasing the gas accumulating within the anchor, beneath the standing valve.

It has heretofore been attempted to release the gas within the anchor, by providing openings or apertures in the upper portion of the anchor. The difficulty in such a construction, is that the fluid cannot be elevated by the action of the pumping plunger, when the level of the fluid falls below the gas outlet apertures. It would of course be disadvantageous to provide gas release apertures in the working barrel, above the standing valve, as this would break the vacuum therein.

In accordance with my invention, I have improved the construction of the standing valve, and have provided means whereby the gas may escape from the anchor, beneath the standing valve, and discharge through aperture or apertures in the working barrel, between the packing of the standing valve. A check valve is provided, which permits of the outward travel of the gases through the standing valve, but closes against inward travel. As a result of this construction, the upper portion of the anchor remains sealed, and the working barrel, above the standing valve, remains sealed, so that the proper pumping action may occur therein. Upon the creation of a partial vacuum within the upper portion of the anchor, in elevating the fluid, the check valve closes, and the anchor is sealed.

In the accompanying drawings, forming a part of this specification and in which like numerals are employed to designate like parts throughout the same,

Figure 1 is a central vertical longitudinal section through the casing and tubing of the oil well, parts in elevation,

Figure 2 is an enlarged side elevation of the improved standing valve,

Figure 3 is a similar view of the standing valve, in position, parts broken away, for the purpose of illustration,

Figure 4 is a side elevation, partly in section, of the lower portion of the standing valve, and,

Figure 5, is a plan view of the same. 60

In the drawings, wherein for the purpose of illustration is shown a preferred embodiment of my invention, the numeral 10 designates the outer casing, and 11 the working barrel, included in the tubing. Mounted to 65 reciprocate within the working barrel is a pumping plunger 12, of the usual construction, having the usual check valve 13, and cups 14. This plunger is reciprocated by the usual plunger rod 15. 70

The lower end of the working barrel is connected with the tubular anchor 16, by means of a threaded fitting or coupling 17, having an inwardly projecting flange 18, provided with the downwardly tapering face 75 or set 19, as shown. The anchor 16 is provided in its lower portion with the usual apertures 20, through which the oil, or other fluid to be raised, passes, from the sand, and enters the anchor. The level of the fluid is 80 above these apertures.

My invention embodies a standing valve, including an upper tubular portion 21, equipped with cups or packing 22, of the usual construction found upon standing valves. The upper tubular body portion is also equipped with the usual valve cage 23, holding the ball check valve. The numeral 24 designates the lower tubular member, provided at its upper end with a tubular extension or neck 25, of reduced diameter, which neck is adapted for engagement with a screw-threaded recess 26, in communication with the bore of the upper tubular member 21. In assembling the upper and lower tubular members, their adjacent ends are retained spaced for affording an annular space or passage 27, for the escape of gases. The lower tubular body portion 24 carries a cup or packing 28, secured to its lower end, by means of a sleeve 29, screw-threaded upon the reduced shank or extension 30. This sleeve is of course tubular, and constitutes an extension of the tubular body portion 24. The outer face of the sleeve 29 tapers downwardly, and is adapted to fit within and be supported by the flange 18. 90

As clearly shown in the drawings, the annular space or recess 27 is arranged between the upper cups or packing 22 and the lower cup or packing 28, and this space 27 is dis- 100 105 110

posed adjacent aperture or apertures 30, formed in the working barrel 11, and arranged between the upper and lower packing. The lower tubular body portion 24 is 5 provided with a gas release port 31, extending longitudinally thereof, and leading into the bore of the same, near its center. The upper end of this port 31 leads into an enlarged port of passage 32, formed in the upper end of the tubular body portion 24, and passing through the face of the shoulder 33. A ball check valve 34 is mounted within the recess or bore 33, and when seated, closes the port 31. As clearly shown in Figure 3, 10 the space or passage 27 is sufficiently narrow whereby the check valve 34 cannot escape from its recess 32.

In view of the foregoing description, it will be seen that as the gas and oil enter the 20 lower portion of the anchor 16, and rises therein, the gas is free to pass upwardly through the lower portion of the standing valve, and will escape through the port 31, recess 32 and apertures 30, to the casing 25 10 and may then pass to the atmosphere. Upon the upper or suction stroke of the pumping plunger, the valve 34 closes the port 31, and hence the upper end of the anchor 16 is sealed. The creation of the usual 30 partial vacuum within the working barrel, above the standing valve, causes the fluid to pass through the standing valve and be elevated in the tubing, as is well known. Particular attention is called to the fact that 35 the apertures 30 in the working barrel are disposed between the upper and lower packing carried by the standing valve, and these apertures are hence out of communication with that portion of the working barrel, 40 above the standing valve, and also out of communication with the upper end of the anchor 16, when the check valve 34 is closed. It might also be stated that the device may 45 be converted into a flood nipple, by pulling the standing valve, and removing the ball check valve 34. In the usual equipment, to produce a flood nipple operation, it will be necessary to pull the tubing, which of course is much more expensive.

50 It is to be understood that the form of my invention herewith shown and described, is to be taken as a preferred example of the same, and that various changes in the shape, size, and arrangement of parts may be resorted to without departing from the spirit of my invention or the scope of the subjoined claims.

Having thus described my invention, I claim:

60 1. In oil well equipment, a casing, a tubing within the casing embodying a working barrel, an anchor connected with the lower end of the working barrel and provided in its lower portion with apertures which are adapted to be covered by the fluid to be elevated, a

standing valve disposed within the lower end of the working barrel between such lower end and the upper end of the anchor, said standing valve embodying a tubular body portion having packing near its upper and lower ends, said tubular body portion being provided with a check valve controlled gas outlet which is positioned between the packing, said working barrel having outlet means positioned between said packing 70 said standing valve further embodying a check valve arranged above the check valve controlled outlet.

2. In pumping apparatus, a casing, a tubing within the casing embodying a working 80 barrel, a tubular anchor secured to the lower end of the working barrel, a standing valve held within the lower end of the working barrel and embodying a tubular body portion, a main check valve, vertically spaced 85 packing elements carried by the tubular body portion, said tubular body portion being provided between the packing elements with a gas escape opening, an outwardly opening check valve to control the passage 90 of gas through said opening, said working barrel being provided between the packing elements with gas outlet means.

3. In pumping apparatus, a casing, a tubing within the casing embodying a working 95 barrel, a tubular anchor secured to the lower end of the working barrel, and a standing valve arranged within the lower end of the working barrel, said standing 100 valve embodying an upper tubular body portion carrying packing and a main check valve, a lower tubular body portion having its upper end connected with the lower end of the upper tubular body portion and spaced therefrom to afford a passage, said lower tubular body portion carrying packing and provided with a gas outlet leading from its bore through the upper end thereof and communicating with said passage, an 105 outwardly opening check valve within said passage, said working barrel being provided with gas outlet means disposed between the upper and lower packings.

4. In pumping apparatus, as a sub-combination, a standing valve including a tubular body portion, upper packing carried by the tubular body portion, lower packing carried by the tubular body portion and spaced from the upper packing, a main check valve carried by the tubular body portion, said tubular body portion being provided between the upper and lower packings with a gas outlet, and an outwardly opening check valve for the gas outlet.

5. In pumping apparatus, as a sub-combination, a standing valve including an upper tubular body portion provided at its lower end with a screw-threaded opening, a check valve carried by the upper tubular body portion, packing carried by this upper tubu- 125 130

lar body portion, a lower tubular body portion provided at its upper end with a screw-threaded stem to enter the screw-threaded recess of the upper tubular body portion, 5 packing carried by the lower tubular body portion, said lower tubular body portion being provided with a gas outlet passage leading through its upper end, and an outwardly opening check valve within said passage.

6. In pumping apparatus, as a subcombination, a standing valve including a tubular body portion, spaced upper and lower packing elements carried by the tubular body portion, said tubular body portion being provided between the spaced upper and

lower packing elements with gas outlet means, and a main check valve carried by the tubular body portion.

7. In pumping apparatus, as a subcombination, a standing valve including a tubular 20 body portion, packing means carried by the tubular body portion and forming a recess which is sealed at its top and bottom by the packing means, said tubular body portion having a gas outlet leading into said recess, a check valve for controlling the passage of gas through the gas outlet, and a main check valve carried by the tubular body portion.

In testimony whereof I affix my signature.
JAMES RINARD.
